UNITED STATES PATENT OFFICE.

FREDERICK A. KURSHEEDT, OF NEW YORK, N. Y.

DESIGN FOR TRIMMING.

Specification forming part of Design No. 5,459, dated January 2, 1872.

SPECIFICATION.

To all whom it may concern:

Be it known that I, FREDERICK A. KURSHEEDT, of New York, in the county of New York and State of New York, have invented a certain new and useful Design for Dress-Trimming; and I do hereby declare that the following is a full, clear, and exact description thereof, reference being had to the accompanying drawing and to the letters of reference marked thereon, which form a part of this specification.

The nature of my design is fully illustrated by the accompanying drawing, to which reference is made.

A represents a piece of plaiting, the plaits running diagonally, and having lace B or its equivalent sewed along the sides. This plaiting is then folded longitudinally, the upper fold being narrower than the lower, making the plaits of the two folds cross each other. A

piece of fluting, C, is then sewed along the folded edge, with a narrow ribbon or band, D, covering stitched on the face to cover the raw edge of the fluting. A colored ribbon may or may not be added between the folds of the plaiting as may be desired, the whole in either case forming a beautiful trimming for a variety of purposes.

What I claim is—

The design for trimming, as shown, consisting of the folded plaiting A, lace B, fluting C, and band D, with or without a colored ribbon between the folds of the plaiting, as herein set forth.

In testimony that I claim the foregoing as my own I affix my signature in presence of two witnesses.

FRED. A. KURSHEEDT.
